UNITED STATES PATENT OFFICE.

CHARLES A. STURTEVANT, OF PLAINFIELD, NEW JERSEY, ASSIGNOR TO
E. C. FULLER COMPANY, OF NEW YORK, N. Y., A CORPORATION OF
NEW YORK.

SIDE REGISTER FOR SHEET-FOLDING AND OTHER MACHINES.

No. 823,002.

Specification of Letters Patent.

Patented June 12, 1906.

Application filed February 17, 1905. Serial No. 246,049.

To all whom it may concern:

Be it known that I, CHARLES A. STURTEVANT, a citizen of the United States, residing at Plainfield, in the county of Union and State of New Jersey, have invented new and useful Improvements in Side Registers for Sheet-Folding and other Machines, of which the following is a specification.

This invention relates to a side register for sheet-folding, printing, ruling, and other machines in which the sheets require to be registered at the side preparatory to being operated upon.

The object of this invention is to produce a register for this purpose which enables the sheets to be more accurately registered at the side than has been possible heretofore, which can be more readily adjusted for different sizes or thicknesses of sheets, and which is superior in its detail construction.

In the accompanying drawings, consisting of two sheets, Figure 1 is a fragmentary sectional elevation of a sheet-folding machine provided with my improved side-registering mechanism. Fig. 2 is a top plan view of the same. Fig. 3 is a fragmentary longitudinal section, on an enlarged scale, in line 33, Fig. 2. Figs. 4, 5, and 6 are horizontal sections in lines 44, 55, and 66, Fig. 3. Figs. 7, 8, and 9 are vertical transverse sections in lines 77, 88, and 99, Fig. 3, respectively.

Similar letters of reference indicate corresponding parts throughout the several views.

The folding-machine shown in the drawings and equipped with my improved side register consists, essentially, of a main frame A, a pair of horizontal folding-rollers B B, tapes C, passing around a receiving-roller D and carrying the sheets over the folding-rollers, and a folding-blade E, whereby the sheets are fed from the tapes between the folding-rollers.

When the sheet comes to rest after being carried by the tapes over the folding-rollers and before being acted on by the folding-blade, the same is registered at the side by my improved side-registering mechanism, which is constructed as follows:

F' represent the upper and lower jaws of the side-registering gripper. These jaws are arranged lengthwise along the side of the path of the sheet to be registered and folded, so that the sheet as it is carried forward by the tapes passes with its side edge between

the jaws of the gripper. The lower jaw consists of a rigid or inelastic plate having a beveled edge for directing or guiding the sheet over the same. The under side of this jaw is provided with a pair of sleeves G G', which are mounted, respectively, on an actuating-rod g and a guide-rod g'. These rods are arranged horizontally and parallel in the machine below the carrying portions of the tapes and are supported at their inner and outer ends in brackets H H' on the main frame. The guide-rod g' is fixed on the brackets H 65 H', but the actuating-rod g is movable thereon. The lower gripper-jaw is frictionally connected with the guide-rod g', so that the same and the parts connected therewith are held in position while the gripper-operating mechanism opens and closes the jaws. This frictional connection is formed by dividing the sleeve G', so that the upper part is integral with the lower jaw, while the separable lower part G² is loosely connected with the upper part by a screw i, loosely connecting said parts on one side of the rod g', a screw i', connected with one part of the sleeve G' and passing loosely through the other part on the opposite side of the guide-rod g', and a spring 75 i², surrounding the screw i' and operating to draw the parts of said sleeve yielding against opposite sides of the guide-rod g'. The other sleeve G is mounted loosely on the actuating-rod g, so that the latter can slide 80 freely through the same, while the lower gripper-jaw is held frictionally on the guide-rod against movement with the actuating-rod.

The upper gripper-jaw consists of an upwardly-tapering block of rubber or other elastic material and is secured at its upper end in a correspondingly-shaped socket or opening j, formed in the upper arm of an elbow-shaped gripper or rock lever J. This 85 lever is pivoted on the rear part of the lower jaw by a horizontal screw or pin k, so as to turn in a vertical plane, and its upper arm, which carries the upper flexible gripper-jaw, projects horizontally forward over the fixed 90 jaw, while its lower arm projects downward in rear of the lower jaw, as shown in Fig. 3.

At the rear or outer end of the lower gripper-jaw the same is provided with an upwardly-projecting wall or standard L, which 105 has a vertical slot l, through which the upper

arm of the gripper-lever projects. The inner or front side l' of this wall serves as the side guide or gage face, which engages the side edge of the sheet and determines the registering position of the same.

The rocking movement of the gripper-lever is effected by means of a slide composed of two sections or cross-heads N N' , which are mounted on the guide-rod and actuating-rod in rear of the gripper. Each of these slides has a complete sleeve n , which is mounted loosely on the guide-rod, and a split sleeve n' , the parts of which are clamped against opposite sides of the actuating-rod by a screw n^2 , as shown in Figs. 8 and 9. The front slide N is provided on its front side with a lug o , which is pivotally connected with the lower arm of the gripper-lever J . The two sections of the slide are adjustably connected by a horizontal screw o' , which has its screw-threaded front end working in a threaded opening in the top of the front slide-section N , while its rear part turns in the rear slide-section, but is compelled to move lengthwise therewith. The preferred construction of this connection (shown in the drawings) consists in seating the screw in upwardly-opening recesses o^2 , formed in lugs o^3 on the upper end of the rear slide-section and a collar o^4 , arranged on the screw and fitting between said lugs.

The actuating-rod g is reciprocated intermittently from a continuously-rotating shaft P by means of a cam p , arranged on said shaft, an upright rock-lever Q , pivoted on the main frame and loosely connected at its upper end with the rear end of the actuating-rod, and a yoke R , sliding on the shaft and provided at one end with a roller r , which engages with the groove of the cam, while its opposite end is connected by a rod r' with the lower end of the rock-lever Q . The cam makes one rotation for every sheet that is fed to the machine and is so timed that the actuating-rod is moved forward to the end of its stroke after the sheet has been fed between the jaws of the gripper, then moves backward to the end of the stroke in this direction, then moves forward a short distance, and then remains at rest while the sheet is being carried away and the next following sheet is fed to the gripper. While the sheet to be registered is being fed between the gripper-jaws the gripper-lever is turned, so that its upper jaw is elevated above the path of the sheets, and the gripper is opened, as shown by dotted lines in Fig. 3. In this position of the gripper-lever its lower arm bears at its front side against the rear end of the lower gripper-jaw, this arm being preferably provided with a bearing face or lug s for engaging the lower jaw.

After the sheet has been fed between the jaws of the gripper the actuating-rod moves forward to the end of its stroke in this direc-

tion, during which time the gripper moves positively with the actuating-rod, and its frictional connection with the guide-rod slips on the latter. During this forward movement of the gripper the registering face l' thereof is engaged with the side edge of the sheet to be registered. During the first part of the subsequent backward movement of the actuating-rod g the gripper does not move with the same, but is held frictionally in place on the guide-rod g' . While the gripper is thus held stationary the slide-section N , which is pivotally connected with the gripper-lever and continues to move backwardly with the actuating-rod, causes this lever to turn and move the upper gripper-jaw downwardly toward the lower jaw, thereby gripping the sheet between them, as shown in Figs. 3 and 7. After the sheet has been thus gripped between the upper and lower jaws the latter, together with the sheet held thereby, are moved laterally with the actuating-rod to the end of the backward stroke of this rod. When the gripper reaches this position, the sheet is properly registered. The lower gripper-jaw is now held frictionally at rest on the guide-rod g' during the first part of the following forward movement of the actuating-rod, and during this time the gripper-lever is turned for lifting the upper jaw from the lower jaw, thereby releasing the sheet. After the gripper has been thus opened the same remains stationary until the registered sheet has been carried away to the folding mechanism or other devices and the next sheet to be registered is fed between the gripper-jaws, when the registering operating is repeated.

In side-registering grippers as heretofore constructed the gripper would not begin its lateral movement with the sheet until the upper flexible jaw was compressed against the sheet on the lower jaw sufficiently to overcome the friction between the lower gripper-jaw and the guide-rod. The beginning of this movement therefore depended on the elasticity of the upper jaw, and since this elasticity is liable to vary the point at which the gripper comes to rest upon being moved laterally varies correspondingly and produces inaccurate registering in the same measure. In order to avoid this, the rocking movement of the lever J in the direction for closing the jaws is arrested positively and the elastic upper jaw is constructed to engage the sheet lying upon the lower jaw in advance of this arrest, and then yield until the closing movement of the rock-lever is positively arrested. The stop for thus arresting the closing movement of the gripper-lever consists, preferably, of a web or bar f , arranged at the rear end or edge of the lower jaw and at the lower end of the slot in the standard, as shown in Figs. 3, 5, and 7. As the upper arm of the gripper-lever moves downwardly,

the elastic jaw carried thereby first engages the sheet lying on the lower jaw and thereafter is compressed until the under side of this arm engages the stop-bar f , when the further movement of the rock-lever in that direction is arrested. The gripper is now compelled to move laterally with the actuating-rod and the sheet is carried with the same into a correctly - registered position. The central part of the stop-bar is preferably provided with a recess f' in order to provide clearance for the upper gripper-jaw, which engages with the adjacent part of the lower jaw, as shown in Fig. 5.

15 For the purpose of adjusting the gripper to different widths of sheets the bolts or screws n^2 are first loosened, after which the slide-sections and the gripper-jaws are moved lengthwise of the guide and actuating-rods approximately into the desired position and then the clamping-screw n^2 of the slide-section N' is tightened for securing the same to the actuating-rod, thereby effecting a coarse adjustment of the gripper. The adjusting-screw o' is now turned in the proper direction for moving the front slide-section N relatively to the rear section N' until the fine or accurate adjustment of the gripper has been produced, after which the clamping-screw n^2 of the front slide-section is also tightened for securing the latter on the actuating-rod. The side-registering device is now ready for use.

25 T represents a curved or inclined guide-plate or guard whereby the sheets while moving forward with the carrying-tapes are directed underneath the upper jaw of the gripper. This guide-plate is arranged above the lower jaw and provided with a rearwardly-opening recess t , through which the upper arm of the gripper-lever moves. For the purpose of adapting this guide to paper of different thickness or quality the same is adjusted vertically by the following means:

35 The rear side of the guide-plate bears against the vertical front face l' of the wall L and is provided with a guide-lug t' , which fits into the vertical slot l thereof. U represents a spring clamping-plate which bears at its ends against the rear side of the wall L on opposite sides of its slot l and is connected by a horizontal clamping-screw v with the guide-lug t' . The clamping-plate is retained in its proper position relatively to the wall by means of a dowel or pin v' , passing through the same and the guide-lug, as shown in Fig. 4.

45 W represents a vertical adjusting-screw, which engages its lower threaded end with a threaded opening in the guide-lug t' , while its upper end turns in the wall L , but is incapable of axial movement therein. The preferred means of effecting the connection between the vertical adjusting-screw and the wall consists in engaging the screw with a laterally-opening recess w in a cross-bar w' at the top of the wall L and providing the screw

55 with collars w^2 , which engage with the upper and lower sides of said bar, as shown in Figs. 3, 6, and 7. Upon turning the screw W in one direction or the other the guide or guard is raised or lowered. When comparatively thick or stiff paper is being side-registered, the guide is raised, so as to leave a wide space between the same and the lower jaw. When, however, thin or soft paper is being side-registered, the guide is lowered, so as to narrow the space between the same and the lower jaw, thereby holding the side edge of the sheet squarely in engagement with the gage-surface l' of the gripper and preventing curling of this edge. By this means the gripper may readily be set for effecting correct register of different kinds and thicknesses of sheets.

I claim as my invention—

1. A side register comprising an inelastic gripper-jaw and an elastic gripper-jaw arranged on opposite sides of the path of the sheets, means for moving one of said jaws toward and from the other, and a positive stop constructed to arrest the closing movement of said actuating means after said jaws are engaged, substantially as set forth.

2. A side register comprising an inelastic gripper-jaw, an elastic gripper-jaw, actuating means for moving one of said jaws toward and from the other, and a positive stop constructed to arrest the closing movement of said actuating means after said jaws are engaged, substantially as set forth.

3. A side register comprising a lower inelastic gripper-jaw, an upper elastic gripper-jaw, a rock-lever carrying said upper jaw, and a rigid stop constructed to arrest the closing movement of said lever after said jaws have been engaged, substantially as set forth.

4. A side register comprising a lower inelastic gripper-jaw, an elastic upper gripper-jaw, a rock-lever pivoted on said lower jaw and supporting the upper jaw on its upper arm, and a stop-bar for positively arresting the closing movement of said rock-lever arranged at the rear of said lower jaw underneath the upper arm of said lever and having a recess which receives said upper jaw, substantially as set forth.

5. A side register comprising a lower gripper-jaw, a lever provided on its upper arm with an upper gripper-jaw, and a reciprocating slide having a forwardly-projecting lug which is pivoted to the lower arm of said lever, substantially as set forth.

6. A side register comprising two gripper-jaws one of which is movable toward and from the other, a reciprocating slide composed of two sections one of which is operatively connected with the movable gripper member, an adjusting-screw having a thread at one end which engages with a correspondingly-threaded opening in one of said sections while its opposite end is arranged in an up-

wardly-opening recess in the other section, and is held against axial movement therein, substantially as set forth.

7. A side register comprising two gripper-jaws one of which is movable toward and from the other, a reciprocating slide composed of two sections one of which is operatively connected with the movable gripper member, an adjusting-screw having a thread 10 at one end which engages with a correspondingly-threaded opening in one of said sections while its opposite end is arranged in upwardly-opening recesses formed in lugs on the other slide-section and has a collar which 15 fits between said lugs, a guide-rod and an actuating-rod upon which said grippers and slide-sections are mounted, and means for clamping said slide-sections on said actuating-rod, substantially as set forth.
8. A side register comprising a lower gripper-jaw having an upright wall on its rear side, an upper gripper, a vertically-adjustable guide sliding on said wall, and an adjusting device for said guide connecting the same 20 with said wall, substantially as set forth.
9. A side register comprising a lower gripper-jaw having an upright wall on its rear side, an upper gripper-jaw, a vertically-adjustable guide sliding on said wall, and an adjusting-screw mounted on said wall and engaging with said guide, substantially as set forth.
10. A side register comprising a lower gripper-jaw having an upright wall on its rear

side the upper part of which is provided with 35 a laterally-opening recess, an upper gripper-jaw, a guide sliding vertically on said wall, and an adjusting-screw engaging its lower threaded end with a threaded opening in said guide and having its upper end arranged in 40 said recess and provided with shoulders or collars bearing against said wall on opposite sides of said recess, substantially as set forth.

11. A side register comprising a lower gripper-jaw having an upright wall on its rear 45 side which contains a vertical slot, an upper gripper-jaw, a guide sliding vertically on the front side of said wall and having a lug fitting said slot, and a clamping-plate secured to said lug and bearing against the rear side of 50 said wall, substantially as set forth.

12. A side register comprising a lower gripper-jaw having an upright wall on its rear side which contains a vertical slot, an upper gripper-jaw, a vertically-adjustable guide 55 sliding on the front side of said wall and having a lug fitting into said slot, a clamping-plate bearing against the rear side of said wall, a clamping-screw connecting said plate and lug, and an adjusting-screw journaled on 60 the wall and engaging with said lug, substantially as set forth.

Witness my hand this 14th day of February, 1905.
